ATTORNEY.

UNITED STATES PATENT OFFICE.

WILLIAM H. MATTHEWS, OF NEWBURGH, NEW YORK.

BEDSPRING SUPPORT.

Application filed June 12, 1922. Serial No. 567,637.

To all whom it may concern:

Be it known that I, WILLIAM H. MATTHEWS, a citizen of the United States, residing at Newburgh, in the county of Orange and State of New York, have invented certain new and useful Improvements in Bed-spring Supports, of which the following is a specification.

This invention relates to supporting frames for bed springs, and has for one of its objects to provide a device of this character, having means whereby the frame may be partly dismembered and folded into a relatively small space for transportation or storage.

Another object of the invention is to provide a device of this character, having means whereby the tension of the spring mattress supporting portion may be easily controlled without detaching any of the parts or removing the mattress or bed clothing.

With these and other objects in view the invention consists in certain novel features of construction as hereinafter shown and described and then specifically pointed out in the claims, and in the drawings illustrative of the preferred embodiment of the invention:

Figure 1 is a plan view, and—

Fig. 2 is a section on the line 2—2 of Fig. 1, looking in the direction of the arrow,

Fig. 3 is an elevation of the "head" end, and—

Fig. 4 is an elevation of the "foot" end, of the improved device,

Fig. 5 is an elevation from the "head" end of the device, partly folded,

Fig. 6 is a detached perspective view of one of the tension applying devices at the "head" end of the device,

Fig. 7 is a sectional detail illustrating a modification in the construction of the tension applying portion of the device.

The improved device is comprised of continuous side or longitudinal rails 10, preferably of L bars, a transverse rail 11 at the head end and a transverse rail 12 at the foot end, the transverse rails being also formed of L bars and the member 11 directed upwardly between the side rails, as shown more clearly in Figs. 3 and 5.

Mounted on the side rails 10 at each end is a bracket device, but as the brackets at each end of the device are alike, the description of one will suffice for all.

Each bracket device includes a base portion 13, each having longitudinally directed guide ribs 14 with their confronting edges overhanging to provide dovetailed channels, as indicated more clearly in Fig. 6.

At their outer ends the members 13 are upturned as shown at 15, the upturned portion being reinforced by an L shaped member 16 riveted or otherwise attached to the under faces of the upper webs of the members 10.

The movable portion of the bracket device comprises a base portion 17 movably engaging the rib members 14 and provided with a dovetailed strip 18 movable between the ribs 14. The base member 17 is upturned at its outer end as shown at 19, and the portions 17 and 19 connected by an obliquely directed portion 20.

A straining bolt 21 passes through the portions 15 and 16 of the frame and the portion 19 of each of the bracket devices, the head 22 of the bolt being at the outer end of the bolt and bearing against the portion 16 and the nut 23 bearing against the member 19.

The transverse bar 11 is preferably formed of an L bar with the horizontal web at the lower side, while the transverse bar 12 is also formed of an L bar but with the horizontal web at the upper side. The vertical web of the bar 11 is cut away at the ends and the horizontal web portions extended downwardly and thence outwardly at the ends beyond the cut-away portion, as shown at 24, to form rests adapted to engage the side rails of the bedstead, not shown. Generally the member 11 will be at the "head" of the bedstead, while the member 12 will be at the "foot".

The member 12 bears at its ends against the inner faces of the portions 19 and 20 of the brackets, as shown.

Attached to the side rails 10 at the foot end, are supports 25 to bear on the bedstead side rails and coacting with the extensions 24 to support the frame detachably on the bedstead side rails at both the head and foot.

The portions of the improved device to which the yieldable bed spring structure is connected are each formed in three or more sections 26, 27 and 28, hingedly united at their confronting ends as shown at 29 and 30.

The portions 26, 27 and 28 are each formed of a section of an L bar, and the outer sections 27 and 28 rigidly connected by screws or other suitable fastening devices 5 31 to the portions 20 of the bracket devices, as shown.

In Figs. 1, 3 and 4, the portions 26, 27 and 28 at the head end are temporarily attached to the vertical web of the transverse member 11 by clamp bolts 33, while the portions 26, 27 and 28 at the foot end are temporarily attached to the horizontal web of the transverse member 12, by clamp bolts 34, the members 11 and 12 being attached only 10 to the members 26, 27 and 28, as shown.

The bed spring or "web" portion of the device may be of any desired construction and generally includes terminal springs 35 with the outer terminals of the springs 20 engaging respectively in apertures 36 in the members 26, 27 and 28, as shown in Figs. 1 and 2.

With the parts connected as shown in Fig. 1, the bed spring is firmly held and supported, and strained to any desired degree by simply manipulating the straining bolts 25 21, as before described.

The improved device is capable of being folded into a relatively small space for shipment or storage, or to move the device from place to place or from room to room, by simply detaching the clamp bolts 33 and 34, and folding the outer head and foot portions 27 and 28 over upon the intermediate 30 35 portions 26, as indicated in Fig. 5.

The portions 11 and 12 will also be released at the same time that the portions 26, 27 and 28 are released, and can be disposed in parallel relation to the side portions 10.

40 The improved device is simple in construction, can be formed of any suitable material, and preferably as light as possible consistent with the strains to which it will be subjected when in use.

45 In Fig. 7, a slight modification in the construction of the means for adjusting the bracket devices is shown, consisting in substituting longitudinally directed slots 38 and clamp bolts 39 in the members 13 for the 50 guide ribs 14 and the guide strips 18, shown in Figs. 1 to 6.

In the modified structure, also, the upturned portion 15 is reinforced and supported by an angle member 40 instead of the

member 16 disclosed in the structure shown 55 in Fig. 6.

Having thus described the invention, what is claimed as new is:—

1. A bed spring support comprising spaced side rails, bracket devices adjustably 60 coupled to the head and foot portions of the side rails, transverse members, each in a plurality of hingedly united sections connected to the bracket devices, said hingedly united sections adapted to support a bed spring, 65 and transverse supporting members detachably connected to the hingedly united members.

2. A bed spring support comprising spaced side rails, bracket devices adjustably 70 coupled to the head and foot portions of the side rails, transverse members, each in a plurality of hingedly united sections connected to the bracket devices, said hingedly 75 united sections adapted to support a bed spring, and transverse supporting members detachably connected to the hingedly united members, one of said transverse members having downturned and laterally extended ends to engage the side rails of a bedstead. 80

3. A bed spring support comprising spaced side rails having guide devices at the ends, bracket devices movably engaging said 85 guide devices, adjusting screws operating to forcibly move said bracket devices longitudinally of the side rails, transverse members, each in a plurality of hingedly united sections connected to the bracket devices, said hingedly united sections adapted to support a bed spring, and transverse supporting 90 members detachably connected to the hingedly united members.

4. A bed spring support comprising spaced side rails having guide devices at the ends, bracket devices movably engaging said 95 guide devices, means carried by the side rails and operating to forcibly move said bracket devices longitudinally of the side rails, transverse members, each in a plurality of hingedly united sections connected to the bracket devices, said hingedly united sections adapted to support a bed spring, and transverse supporting members detachably connected to the hingedly united members. 100

In testimony whereof, I affix my signature 105 hereto.

WILLIAM H. MATTHEWS.
